SOAP AND WATER MIXER

Filed March 3, 1930

UNITED STATES PATENT OFFICE

AARIEL E. GOODLOE OF CHATTANOOGA, TENNESSEE, ASSIGNOR TO READY-SUDZ COMPANY, OF CHATTANOOGA, TENNESSEE, A CORPORATION OF TENNESSEE

SOAP AND WATER MIXER

Application filed March 3, 1930. Serial No. 432,840.

My invention relates to a device for producing a soapy solution or a mixture of soap and water and it is an object of said invention to provide a receptacle for soap in which adjustable means are provided permitting a discharge of the soapy solution as long as the materials are present in the receptacle.

A further object is to provide a simple, compact and durable means for supplying the liquid component to the soap and for regulating the supply and direction thereto.

Referring to the accompanying drawings, which are made a part hereof and on which similar reference characters indicate similar parts,

Figure 1 is a view in elevation of one application of my invention,

Figure 2, a cross sectional view of the pressure fluid nozzle,

Figure 3, a view of the pressure fluid nozzle looking upward in Figure 2,

Figure 4, an enlarged detail view of the intake end of the conduit and screen,

Figure 5 shows a modified form of my invention, and

Figure 6 still another modified form of my invention.

In the drawings reference character 10 indicates a receptacle or container for soap 11, the upper end 12 of the container is provided with an opening 13 in which a spherical nozzle 14 is rotatably secured, said nozzle having a perforated base 15 through which the liquid component may enter the receptacle, and a hollow rod or sleeve 16 extending from said base through the spherical nozzle and terminating in the opposite side. A shaft 17 is rotatably secured within said sleeve having a disk 18 provided with blades mounted on the lower end beneath the base 15 and an indicator finger 19 and a finger grip 20 mounted on the other end exteriorly of the nozzle, the disk 18 being rotated by the shaft 17 may be positioned beneath the perforations of the base so that the liquid may be directed laterally instead of directly downward upon the soap. The conduit or hose 21 is connected to a manually operable valve 22, said valve being connected to the spherical nozzle serv-

ing as means for supplying the liquid to the receptacle.

A flexible hose 23 extends upwardly through the soap 11, the upper end 24 being of funnel-like shape and the sides perforated. A piece of screen gauze 25 is secured to the end which permits the soapy mixture to enter the flexible hose 23 and prevents any large particles of soap from entering which might cause a clogging of the same and also to prevent the end 24 from sinking below the surface of the soap. The lower end of the hose projects from the receptacle through an opening at the bottom which is provided with a ring 26, said ring, due to its constriction, prevents leakage around the hose and breakage of the hose and yet allows the hose to be freely pulled therefrom. The screen gauze 25 is secured to the upper end 12 of the receptacle by means of a bolt 27 passing through the screen and the end of the receptacle and a nut 28 on the outside. This prevents any dislodgment of the hose while the receptacle is being shipped or being filled with soap.

A collar 29 may be placed about the hose 23 below the enlarged end which prevents the top of the hose from being pulled entirely down to the surface of the soap and in this manner a sheet of water of any desired depth is formed on the soap 11. The water from the nozzle 14 strikes this sheet instead of the soap and a much quieter mixing is obtained than with direct impact on the soap.

By simply removing the nut 28 the bolt 27 drops into the receptacle and there remains until the receptacle is empty. The flow of water is regulated by the valve and spherical nozzle to produce a mixture of the desired constituency.

As the soap 11 is worn away by the impact of the water the flexible hose 23 is pulled down until the screen 25 or the collar 29 rests on the soap and thereby draining the soapy mixture from the receptacle. In this manner the contents of the receptacle may be fully exhausted.

Figure 5 is a modification of my invention. The drum or barrel 30 containing soap of a constituency that will stand up may be laid upon its side and a stream of water may be

directed through the conduit 31 against said soap forming a soapy mixture which may be withdrawn through the outlet 32 into any suitable container.

Figure 6 is still another form of my invention in which the drum or barrel 33 containing soap is provided with a series of plugged openings 34 in which a faucet 35 may be inserted. As the water enters the drum 33 through the conduit 36 striking the soap forming a soapy mixture which may be withdrawn to a point in line with the faucet and in order to remove more of the soapy mixture it will be necessary to move the faucet into next lower outlet.

It will be obvious to those skilled in the art that various changes may be made in my device without departing from the spirit of the invention and therefore I do not limit myself to what is shown in the drawings and described in the specification, but only as indicated in the appended claims.

Having thus fully described my said invention, what I claim as new and desire to secure by Letters Patent, is:

1. A device for dispensing a soap solution comprising a container for soap, means for forcibly projecting a jet of water against said soap, and means for conducting the formed solution from the surface of the soap comprising a flexible hose extending through said soap and slidably vertically therein to position the intake end adjacent the surface of the soap, substantially as set forth.

2. A device for dispensing a soap solution comprising a container for soap, means for forcibly projecting a jet of water against said soap, means for conducting the formed solution from the surface of the soap comprising a flexible hose extending through said soap and slidably longitudinally therein to position the intake end adjacent the surface of the soap and a disk adjacent the end of the hose for limiting the downward motion of said hose with respect to the level of the soap, substantially as set forth.

3. A soap and water mixer comprising a receptacle for soap, a spherical fluid nozzle rotatably secured to said receptacle, a water supply conduit connected to said nozzle, manually operable means for controlling the flow to said nozzle and for deflecting the water laterally from said nozzle, and means for removing the solution from said receptacle comprising a flexible conduit extending up through the soap and being slidable therein to adjust its intake end to the level of the soap in the receptacle, substantially as set forth.

4. A soap and water mixer comprising a receptacle, a discharge passage from said receptacle, a screened funnel-like intake connected to said discharge passage, means for controlling and directing the flow of water to said receptacle, said means comprising a spherical nozzle having a plurality of perforations through which water may be sprayed into the receptacle and a bladed disk pivoted beneath said nozzle, a shaft journaled in said nozzle and attached to said disk to move it to cover any desired number of said perforations to deflect a portion of the water issuing from the nozzle laterally into the receptacle and means on the shaft for indicating the position of the blades on the disk relative to said perforations, substantially as set forth.

5. A soap and water mixing and dispensing device comprising a tank adapted to contain a soap paste, a flexible tube mounted in the container having its lower end passing through an opening near the bottom of the container and having its intake end positioned above the level of the soap paste in the container, the intake end having a disk adjacent its end to position the inlet to the tube slightly above the level of the paste in the container, said tube being slidable to maintain the intake end adjacent the level of the soap, substantially as set forth.

6. A soap and water mixing and dispensing device comprising a tank adapted to contain a soap paste, a flexible tube mounted in the container having its lower end passing through an opening near the bottom of the container and having its intake end positioned above the level of the soap paste in the container, the intake end having a disk adjacent its end to position the inlet to the tube slightly above the level of the paste in the container, said tube being slidable to maintain the intake end adjacent the level of the soap, and a screen positioned over the intake end, said screen having means associated therewith for holding the tube in elevated position during moving of the container to prevent injury to the tube and screen, substantially as set forth.

In witness whereof, I have hereunto set my hand at Chattanooga, Tennessee, this 20th day of February, A. D. nineteen hundred and thirty.

AAREIEL E. GOODLOE.
